UNITED STATES PATENT OFFICE

2,401,963

ELECTRIC CIRCUIT BREAKER

Earl B. Rietz, Lansdowne, and Dell K. Tower,
Newton Square, Pa., assignors to General Electric Company, a corporation of New York

Application May 7, 1943, Serial No. 436,066

5 Claims. (Cl. 200—150)

1

Our invention relates to electric circuit breakers for interrupting high voltage power circuits, more particularly to power circuit breakers having means for inserting an impedance, such as a resistance in the circuit upon opening of the breaker for controlling transient conditions and facilitating interruption of the circuit, and has for its principal object the provision of an improved circuit breaker of the blast chamber type having an impedance or resistance element incorporated in the chamber construction to form an interrupting unit that is electrically efficient and simple and compact in construction.

Our invention will be more fully set forth in the following description referring to the accompanying drawing, and the features of novelty which characterize our invention will be pointed out with particularity in the claims annexed to and forming a part of this specification.

Referring to the drawing, Fig. 1 is an elevational view, partly in section, of an oil circuit breaker embodying the present invention, Fig. 2 is an enlarged sectional view of one of the interrupting chambers shown in Fig. 1, and Fig. 3 is a plan view taken along the line 3—3 of Fig. 2.

The oil circuit breaker shown by Fig. 1 is of the high voltage type, such as that used in power transmission systems. The circuit breaker comprises essentially an oil tank 1 having a top frame structure 2 in which are mounted the high voltage insulating bushings 3 and 4 for the lead-in conductors 5 and 6, respectively. The insulators and lead-in conductors extend into the oil tank 1 and have attached to their lower ends the contact containing interrupting chambers generally indicated as 7 and 8, respectively. The interrupting chambers and the insulators are rigidly interconnected by an insulating brace 9.

For cooperating with the fixed contact structure hereinafter described within the interrupting chambers, a movable bridging contact member 10 having hollow contacts 11 and 12 is vertically movable by an insulating operating rod 13 to make and break the circuit within the interrupting chambers. The bridging member is suitably operated by mechanism (not shown) within the dome 2. In normal operation the interrupting chambers are immersed in a suitable insulating and arc extinguishing liquid as indicated, such as circuit breaker oil, so that when the movable bridging contact is in the lower open circuit position illustrated the fixed contacts associated with the lead-in conductors 5 and 6, respectively, are effectively insulated from each other by a large oil gap.

2

Referring more particularly to Fig. 2 which shows an enlarged sectional view of the contact containing chamber 8, the contact containing chamber is supported at the lower end of the insulator 4 by means of a metallic adapter 14 that is in turn electrically connected to the lower end of the lead-in conductor 6. The adapter has secured thereto, as by screw-threaded engagement, a strong metal cylinder 15 serving as the main mechanical structure of the interrupting or blast chamber 8. The adapter also has mounted in depending relation therefrom a substantially fixed butt contact 16 that is also electrically connected at 17 to the adapter. The butt contact is suitably mounted for limited "wiping" movement against the bias of its spring 18.

A floating contact 19 located intermediate the fixed contact 16 and the bridging contact member 12 is mounted within the chamber on an insulation disk 20 with numerous vent holes 20' extending through it that is secured between a pair of insulating cylinders 21 and 22. The floating contact 19 is biased downward by a spring 23 toward following engagement with the contact 12. In closing, the contact 12 first engages the contact portion 19a of the floating contact and pushes it upward against the bias of spring 23 until the contact portion 19b firmly engages the fixed contact 16. In opening, lowering of the contact 12 first causes separation of the contacts 16 and 19b, and subsequently separation of the contacts 19a and 12. This sequential formation of two breaks in series causes the arcing pressure generated at the break 16—19b to be utilized to blast oil through the interrupting break 19a—12. This is generally known as "oil-blast" action. This type of oil circuit breaker is well known in the art and further description of the arc interrupting process is unnecessary.

As previously stated, contact containing chamber 8 comprises essentially a metal pot or cylinder 15 for withstanding high arcing pressures generated within the oil-blast chamber incident to circuit interruption. The inner wall of the cylinder is insulated by an insulating cylinder or sleeve 24 and also by the sleeves 21 and 22 previously described for supporting the disk 20. The insulating sleeves are positioned at the upper end of the cylinder by a ring 15a. The lower end of the steel pot is flanged inwardly at 15b for positioning the aforesaid insulating sleeves and for supporting the insulating throat bushing 25 that is held in position by an insulating clamping ring 26 bearing on the flange 15b. The throat bushing 25 forms the passage through which the contact

12 moves into the oil-blast chamber and in which the arc is drawn upon separation of the contacts 18a and 12.

In accordance with our invention the outer wall of the chamber comprises a combined insulating sleeve and resistor unit, the insulating sleeve 21 fitting closely over the pot 15 and extending from near the top of the pot structure to an arcing member 28 hereinafter described, secured to the lower end of the pot, and the resistor 29 being wound about the sleeve 21 in grooves in the form of a helix. The upper terminal of the resistor is electrically connected at 29a to the top of the pot 15 and the lower terminal is electrically connected in any suitable manner at 29b to the arcing member 28. In the specific arrangement shown the resistor unit above described is further insulated and shielded by an insulating sleeve 30 mounted on an outer flange of the arcing member at 31 and suitably spaced from the resistor as indicated at 32. In another arrangement the resistance supporting sleeve 21 is suitably carried by an insulating collar secured to the lower end of the throat bushing 25.

The arcing member 28 is shown also in plan view by Fig. 3 and comprises a disk-like conducting structure secured directly by fibre holding studs 33 to the pot flange 15b. In an alternative arrangement the arcing member 28 can be directly secured to the insulating collar above referred to.

When clamped in the Fig. 2 position by the stud nuts 33a against the insulating ring 26 the arcing member is insulated from the metal pot but is electrically connected to it through the resistor 29 and through the screw thread mounting to adapter 14. At the exhaust end of the throat bushing the arcing member forms four electrode portions 28a spaced approximately 90 degrees apart and extending substantially to or slightly beyond the periphery of the throat opening. It will therefore be seen that the contact 12, in moving from the chamber, has slight mechanical clearance at the electrodes 28a but usually touches some of them in operation because practically it cannot be perfectly centered.

The operation of the circuit breaker is as follows: When the circuit breaker is closed the power circuit includes the lead-in conductor 6, adapter 14 and the contacts 16, 18 and 12. Although the contact 12 may touch 28a, the resistor 29 does not carry an appreciable part of the normal power current in the closed circuit position of the breaker. When the breaker is opened the contacts separate in the sequence above described with the result that the interrupting arc between 18a and 12 is subjected to the oil blast. The contact 12 moves through the throat passage during interruption of the power arc at a current zero by the oil blast. Immediately after momentary interruption at a current zero the returning voltage between the contacts 18 and 12 causes current to flow through the resistor either because contact 12 touches 28a or the voltage breaks down the gap at one or more of the arcing electrodes 28a (due to the short gap between the electrode and the contact 12 as compared with the main interrupting gap at the break 18a-12). The resistor 29 is thereby inserted in series with the power circuit so that the resistance circuit now shunts the main chamber contacts.

The magnitude of the arc current is correspondingly decreased by the resistance and the difficulty of completely interrupting the circuit is greatly diminished, particularly in the case of circuits having high rates of increase of the re-

covery voltage and also in the case of capacitance switching. In the former case the rate of increase of recovery voltage is greatly reduced and the power factor is improved thereby simplifying the problem of interruption, and in the latter case high switching over-voltages are prevented in the manner described in a copending application Serial No. 477,400, filed February 27, 1943 by Boehne and Peterson for "Means for eliminating the switching over-voltage hazard in alternating current circuits" and assigned to the same assignee as the present invention, now Patent No. 2,391,672, issued Dec. 25, 1945.

The ohmic value of the resistance at 29 forms no part of the present invention and depends on the characteristics of the circuit to be controlled.

When the comparatively weak arc current through the resistor is finally extinguished by the cooling effect of the oil, further downward movement of the contact 12 serves to increase the oil gap for isolating the contacts from each other so that there is no danger of flashover or restriking of the arc.

It will therefore be seen that we have provided an efficient, simple and compact interrupting unit that occupies practically no more space within the oil tank than conventional interrupting chambers and that is easy to inspect or repair. For example, the resistor unit can be readily removed from the breaker and replaced independently of the main chamber and the contacts therein so that complete disassembly of the chamber construction is unnecessary. Also the complete contact assembly can be removed as a unit by unscrewing it from the adapter 14. Due to the compactness of the unit, the size of the oil tank need not be increased to provide additional essential electrical clearance.

In certain cases, it is within the scope of our invention to provide wiping contact engagement between the auxiliary electrode structure and the movable contact 12. In this arrangement, the resistance is inserted in the circuit through current flow. Also, it is within the scope of our invention to provide, for example, a molded cylinder of suitable resistance material in lieu of the insulating cylinder 27 and wire resistor 29.

Insofar as system operation is concerned advantages of our invention include improved system stability, reduction of insulation failures due to switching over-voltages and subsequent interruption of service, and increased capacitive kva. switching ability of the breaker, thereby making possible increased breaker economy as well as the release of more wattless kva. for useful manufacture by the greater use of capacitor banks for power factor correction.

It should be understood that our invention is not limited to specific details of construction and arrangement thereof herein illustrated, and that changes and modifications may occur to one skilled in the art without departing from the spirit of our invention. For example, the oil-blast chamber may be of the well-known "side-vent" type wherein the exhaust port is located in the side wall of the chamber instead of at the bottom through which the movable contact passes. In this arrangement the operation is essentially the same except that the oil blast is directed 70 transversely instead of longitudinally through the arc.

What we claim as new and desire to secure by Letters Patent of the United States is:

1. An electric circuit breaker comprising an insulating and arc extinguishing liquid, an arc in-

interrupting blast chamber immersed in said liquid, contacts separable in said chamber to interrupt the circuit, a resistor associated with said chamber and electrically connected to one of said contacts, an arcing electrode also associated with said chamber at the blast opening thereof, and means for operating said contacts so that the circuit through said contacts is interrupted while another of said contacts is moving through said exhaust opening adjacent to said arcing electrode, said resistor being arranged to shunt said contacts in accordance with current flow between said arcing electrode and said moving contact whereby said resistor is inserted in the circuit to be interrupted.

2. An electric circuit breaker comprising an insulating and arc extinguishing liquid, an arc interrupting oil blast device having an exhaust opening immersed in said liquid, contacts including a movable contact separable in said device to interrupt the circuit, a resistor associated with said device and electrically connected to one of said contacts, an arcing electrode connected to said resistor and positioned at said exhaust opening so as to have slight mechanical clearance with said movable contact, and means for operating said movable contact so that the circuit through said contacts is interrupted while said movable contact is moving through said exhaust opening adjacent to said arcing electrode, said resistor being arranged to shunt said contacts upon completion of circuit at the clearance gap between said arcing electrode and said movable contact whereby said resistor is inserted in the circuit to be interrupted.

3. An electric circuit breaker comprising an insulating and arc extinguishing liquid, an arc interrupting oil blast chamber having an exhaust opening immersed in said liquid, contacts including a contact movable through said exhaust opening separable in said chamber to interrupt the circuit, a resistor mounted on said chamber and electrically connected to one of said contacts, an arcing electrode connected to said resistor and positioned at said exhaust opening and having slight mechanical clearance with said movable contact, and means for operating said movable contact so that the circuit through said contacts is interrupted while said movable contact is passing through said exhaust opening adjacent to said arcing electrode, said resistor being arranged to shunt said contacts upon com-

pletion of circuit at the clearance gap between said arcing electrode and said movable contact whereby said resistor is inserted in the circuit to be interrupted.

- 5 4. An electric circuit breaker of the oil-blast type comprising an insulating and arc extinguishing liquid, an oil-blast arc interrupting chamber having an exhaust opening immersed in said liquid, contacts including a contact movable through said exhaust opening separable in said chamber to interrupt the circuit, a resistor generally in the form of a helix surrounding said chamber and electrically connected to one of said contacts, an arcing electrode disposed at said chamber exhaust opening connected to said resistor, and means for operating said movable contact so that the circuit through said contacts is interrupted while said movable contact is moving through said exhaust opening adjacent to said arcing electrode, said resistor being arranged to shunt said contacts upon voltage breakdown of the clearance gap between said arcing electrode and said movable contact whereby said resistor is inserted in the circuit to be interrupted.
- 10 15 5. An electric circuit breaker of the oil-blast type comprising an insulating and arc extinguishing liquid, an arc interrupting device including a chamber having an exhaust opening immersed in said liquid, contacts including a contact movable through said exhaust opening separable in said chamber to interrupt the circuit, a resistor mounted on said chamber and electrically connected to one of said contacts, an arcing electrode comprising a conducting ring-like structure substantially surrounding said movable contact and having slight mechanical clearance therewith, said arcing electrode being connected to said resistor and located substantially in alignment with said exhaust opening at said exhaust opening, and means for operating said contact so that the circuit through said contacts is interrupted while the moving contact is passing through said exhaust opening adjacent to said arcing electrode, said resistor being arranged to shunt said contacts upon voltage breakdown of the clearance gap between said arcing electrode and said movable contact whereby said resistor is inserted in the circuit to be interrupted.
